UNITED STATES PATENT OFFICE.

JAMES BEESLEY AND ARTHUR B. BENJAMIN, OF NEW YORK, N. Y., ASSIGNORS
TO THE CLARK ELECTRIC COMPANY, OF SAME PLACE.

DESIGN FOR AN ELECTRIC-ARC LAMP.

SPECIFICATION forming part of Design No. 20,489, dated January 20, 1891.

Application filed October 20, 1890. Serial No. 368,725. Term of patent 14 years.

To all whom it may concern:

Be it known that we, JAMES BEESLEY and ARTHUR B. BENJAMIN, citizens of the United States, residing in New York city, county of New York, and State of New York, have invented and produced a new and original Design for Electric-Arc Lamps, of which the following is a specification, reference being had to the accompanying drawing, forming part thereof.

The figure is a side elevation of an electric-arc lamp, showing our design.

The leading feature of our design consists in a globe and a lantern-like frame closely surmounting it.

The frame, which is cylindrical in general contour, has a dome-shaped top *a* and is composed of three connected bands *b* *b'* *b''*, horizontally fluted into a series of annulets, the upper band *b* being at the base of the dome *a*.

Between the annulet-bands *b* and *b'* is a scroll-band *c* of two rows of double volutes, and below band *b'* is a fringe *c'* of similar double volutes. The larger and lower band *b''* is surmounted by a similar band *c''* of double volutes, and between this lower band and the upper bands is a series of rods *d*, hav-

ing spherical knobs *d'*. This portion of the frame so far described has somewhat the shape and appearance of an architectural lantern. 30

Above the dome *a* is a ball *e*, having vertical flutes divided by a plain central horizontal band *e'*, and above the ball is a column *f*, surmounted by a capital *g*, the whole having somewhat the appearance of an ornamental flue or chimney. 35

Below the annulet-band *b''* is an inverted-pear or balloon shaped globe *h*, to which the band *b''* *c''* appears as a crown. 40

Having now described our invention, what we claim is—

The design for electric lamps, the same comprising a globe and a lantern-like frame closely surmounting it, as shown and described. 45

In witness whereof we have hereunto signed our names in the presence of two subscribing witnesses.

JAMES BEESLEY.
ARTHUR B. BENJAMIN.
